UNITED STATES PATENT OFFICE.

JOHN EDWARD THORNTON, OF MANCHESTER, ENGLAND.

CARDBOARD BOX.

No. 896,600.

Specification of Letters Patent. Patented Aug. 18, 1908.

Application filed October 31, 1899. Serial No. 735,432.

To all whom it may concern:

Be it known that I, JOHN EDWARD THORNTON, subject of the Queen of Great Britain, and residing at Manchester, in the county of 5 Lancaster, England, (whose postal address is Worsley Mills, Hulme, Manchester aforesaid,) have invented certain new and useful Improvements in Cardboard Boxes.

Card board boxes of the non-collapsible 10 type are now most commonly made by stamping out the bottom sides and ends from a single piece of material by cutting away the corner pieces and then forming the angles of the boxes where the edges abut by 15 strengthening strips of material pasted glued or otherwise attached thereto or by metallic clips or the like.

I find a very strong and durable angle may be made to the box in an entirely different 20 way by cutting the edges of the card board destined to form the angles with a number of flat projections and recesses of interlocking dovetail or other approximate or similar shape and bending over such projections intermediate of their length to form the angles of the box so that the projection on one 25 side enters the space between the projections on the other side.

The invention will be fully described with 30 reference to the accompanying drawings in which several forms of box constructed in accordance with the invention are illustrated as examples.

Figure 1. is a perspective view of box. 35 Fig. 2. is a perspective view of box showing modified form of joint. Fig. 3. is a perspective view of box turned bottom upwards showing jointing round the bottom edges. Fig. 4. is an extended blank of box shown in 40 Fig. 1. Fig. 5. is an extended blank of box shown in Fig. 2. Fig. 6. is an extended blank of sides and ends of box shown in Fig. 3. Fig. 7. is a blank for bottom of box shown in Fig. 3. Fig. 8. is an extended 45 blank of sides and ends of box with modified form of joints. Fig. 9. is a blank for bottom of box shown in Fig. 8.

The box *a* is rectangular shape and may be of any size the parts being jointed together 50 either at the vertical edges or around the bottom. Along the edges *b* that are to be jointed together are formed a number of recesses

or notches *c* and projections *d* alternating with each other of such a shape as to interlock one into the other the projection *d* being 55 wider at its extremity and the space or notch narrower. The projections on their inner side are scored bent or creased along the lines *x-y* to cause them to bend at right angles intermediate of their length so that when the 60 edges *b* are brought together the two sets of projections lie in the same flat plane and the end of the projections *d* fit into the corresponding recesses or notches *c* and interlock or dovetail therewith. The projections *d* on 65 the end interlock or dovetail with the spaces or notches *c* on the sides and the projections *d* of the sides interlock or dovetail with the recesses or notches *c* on the ends.

The angle formed at the edge by bending 70 the projections intermediate of their length on the line *x-y* prevents the interlocking parts being pulled asunder but they may be further secured by glue gum mucilage cement or other adhesive material applied to 75 the edges to give additional strength.

The boxes *a* may be shaped by cutting away the corner pieces and jointing the angles as in Figs. 1, 2, 4 and 5 or the bottom and sides may be made separately and jointed 80 along the bottom edge as in Figs. 3, 6, 7, 8 and 9.

What I claim as my invention and desire to protect by Letters Patent is:

In a rectangular card board box, or case 85 having adjacent sides and ends, the combination with one side formed with a plurality of interlocking projections creased and bent at right angles intermediate of their length to form the corner of the box, of another side 90 also formed with a plurality of interlocking projections creased and bent at right angles intermediate of their length, the projections on one side locking into those on the other side and holding securely together without 95 cement, substantially as described.

In witness whereof, I have hereunto signed my name in the presence of two subscribing witnesses.

JOHN EDWARD THORNTON.

Witnesses:

FRED. C. HARRIS,
WALTER J. SKERTEN.
